OSCAR J. HOLMES, OF TULSA, OKLAHOMA.

ONE-PIPE SPRINKLER SYSTEM.

Application filed August 9, 1920. Serial No. 403,226.

This invention relates to sprinkler systems of the character adapted to be installed in buildings where it is desired to have sprinkler protection against fire throughout the building, and is more particularly directed to a novel and efficient sprinkler for delivering foam in the immediate vicinity of a fire in an entirely automatic manner and through the employment of simple and efficient mechanism.

All of the prior systems which are adapted to deliver foam in the vicinity of a fire, so far as I am aware, embody a two pipe system, one of which pipes conveys an acid to the vicinity of the fire, and the other of which pipes conveys a foam forming solution to the same vicinity, and in the event of a fire, both pipes are simultaneously unsealed in the vicinity of the fire and the acid and foam forming solution mixed substantially at the point of delivery. While these systems operate with more or less efficiency, they have the inherent disadvantage of requiring two separate and distinct piping systems, one for the acid and the other for the foam forming solution, which are not only an encumbrance to the building, but are expensive to install because of the necessity of duplicating the piping throughout the building.

With these considerations in mind, the prime object of the present invention is to provide a sprinkler system for the delivering of foam to the locality of the fire, through a single pipe system, thereby entirely dispensing with substantially one half the piping heretofore necessary for the carrying out of this function.

A further and important object of the invention is to provide in a foam delivery system, an independent normally inert pressure charge automatically rendered operative by the opening of a sprinkler head and adapted, when brought into operation, to develop sufficient pressure for the purpose of causing acid and alkaline solutions to be brought together and maintained under pressure, thereby preventing expansion and the forming of foam or bubbles as they pass through the system to the point of discharge, said acid and alkali being preferably combined after leaving their respective

containers and before arriving at the sprinkler head through which they find outlet in the form of foam or bubbles.

Another feature of the invention is embodied in means whereby the delivery of the extinguishing medium may be controlled from any floor of the building in which the installation is made, preferably through the releasing of the pressure at any time, for the purpose of stopping the delivery of the extinguishing medium. Heretofore, it has usually been necessary to go to a common point in the system, adjacent the pressure tank, usually in the basement, in order to shut off any particular part of the system.

A marked practical advantage inherent in a further feature of the invention is found in the improved sprinkler head, which I preferably employ in conjunction with this system. In sprinkler heads as usually constructed, the extinguishing medium finds exit through an outlet, from which it is thrown against a baffle plate, which throws the spray in all directions. When such an apparatus is employed to deliver foam, the spray is so broken up that efficient formation of foam is precluded, since the solution which would form the bubbles are broken up into such small particles as to seriously impair their efficiency in blanketing the fire.

In accordance with the present invention, I provide a chamber into which the fire extinguishing medium, upon leaving a particular outlet of the system, is delivered and in which such material is held back until a sufficient amount of said material has accumulated to substantially fill the chamber to allow of the entrapping of the gas to a sufficient extent to form bubbles which are forced out through the openings provided in the walls of the chamber. One of such openings is preferably in the form of a slot extending entirely around the chamber, whereby the exit of the bubbles therefrom is substantially in the form of a lateral projected sheet, thereby giving maximum distribution of the material. In practice, this lateral projected sheet is somewhat the shape of an umbrella.

Features of the invention, other than those adverted to, will be apparent from the hereinafter detailed description and

claims, when read in conjunction with the accompanying drawings.

The accompanying drawings illustrate one practical embodiment of the present invention, but the construction therein shown is to be understood as illustrative, only, and not as defining the limits of the invention.

Figure 1 is a diagrammatic showing of a system embodying the present invention.

10 Figure 2 is an enlarged detail of a portion of the system shown in section; and,

15 Figure 3 is a central section of an improved foam forming sprinkler head preferably employed in conjunction with the system as shown.

Referring to the drawings, 1 designates a tank or other form of receptacle adapted to contain an alkaline foam forming material, 2 is a second tank or receptacle for containing an acid which, when mixed with the material in the tank 1 will result in the formation of foam, and 3 is a tank or casing containing the means for placing the contents of the tanks 1 and 2 under pressure for the purpose of causing the flow of material contained in said latter tanks to points of mixing and discharging. The tanks 1, 2 and 3 may be mounted in any suitable position within a building and may be supported in any desired way, or such tanks may be formed within a main tank by partitioning off different portions thereof. The invention is not limited to these details of construction.

35 As shown, the tank 3 is connected to the tank 1 through suitable piping 4 or a duct above the normal material level in the tank 1, while the tank 1 is, in turn, connected to the tank 2, through any suitable form of connection, piping or a duct 5, so that if pressure is generated in the tank 3, it will be communicated equally to the tanks 1 and 2 through the connections 4 and 5 specified, and such pressure will, manifestly, be supplied to the material within said tanks 1 and 2 above the surface of the material therein.

50 The material in the tank 1 is adapted to find exit therefrom through a pipe 6, which extends through the top of the tank from a point near the base thereof, while the material from the tank 2 is adapted to be exhausted therefrom through a pipe 7, which extends from a point near the base of the tank 2 through the top of said tank. The upper ends of the pipes 6 and 7 come together in a service T or coupling 8, which has a single outlet pipe 9. The materials from which the pipes 6 and 7 are constructed are such as not to be acted upon by the materials contained in the respective tanks. The pipe 9 leads to a pipe 10 to which it is connected by a coupling 11 and said pipe 10 forms the stand pipe of the sprinkler system. This pipe passes through the several floors of the building, one of which is desig-

nated 12 in Figure 1, and at each floor is provided with laterals 13 having therein sprinkler heads 14 arranged at suitable intervals along said laterals.

A check valve 15 is included in the pipe 9 near the connection 8 and serves to preclude the retrograde flow of material from the pipe 10 through the pipe 9.

Positioned within the lower portion of the casing or tank 3 is a stoneware jar or receptacle 16, adapted to contain a suitable acid. This jar, as shown, extends for substantially one half of the height of the tank 3, and the upper half of said tank is provided for the reception of a wire basket 17, which is suspended by means of a rod 18 passing through the top of the tank. The rod 18, as stated, passes through the top of the tank and is normally maintained in elevated position by means of a detent or latch 19 controlled by a diaphragm regulator 20, mounted on top of the tank 3, as best shown in Figure 2.

The diaphragm regulator 20 embodies a diaphragm 21, extending across the casing of the regulator and dividing the interior of the casing into an upper and lower chamber 22 and 23, respectively. The upper chamber 22 is in communication with the lower end of the stand pipe 10, while positioned within the lower chamber 23 is a head 24 of a plunger 25 which depends from the head 24 and is pivotally connected at 26 to one of the detents 19. The detent is pivoted intermediate its ends as at 27, and its free end normally engages with a shoulder or notch 28 in the rod 18.

In the normal condition of the structure of this invention, sufficient pressure is normally exerted through the pipe 10 on to the upper surface of the diaphragm 21 to maintain the plunger 25 in depressed position to elevate the free end of the detent 19 and effect the holding of the rod 18 in elevated position with the result that the wire basket 17 which is adapted to contain a suitable alkali is suspended above the surface of the acid contained in the earthen vessel 16. If, in the event of fire, however, the pressure in the pipe 10, normally sustained through the sealing of the respective sprinkler heads 14, is broken, through the opening of one of the sprinkler heads, it will be sufficient to flex the diaphragm 21 downwardly as shown in Figure 2, with the result that the weight of the wire basket 17 and its contents, will effect a tilting of the detent 19 to release the free end of the detent from the shoulder 28 and allow the wire basket 17 to descend into the acid vessel 16.

In order that such descent of the wire basket may be unrestricted when once released by the detent, the rod 18 is preferably provided with a clutch connection 29, shown in Figure 2. This clutch connection may be in the form of two interfitting teeth, as

shown, and these teeth normally maintained in interlocking relation when the rod 18 is elevated by occupying a position within a sleeve or collar 30, forming part of a stamping 31, riveted interiorly of the tank as at 32. When the rod is released, its descent will move the clutch to a point below the sleeve 30 and permit of the separation of the teeth so that the basket 17 will be released and 10 will drop into the acid within the container 16.

The upper portion of the rod 18 is preferably provided with two fixed collars 33 and 34. When the rod is released, the collar 33 15 engages with the upper end of a boss 35 through which the rod passes in order to keep the upper portion of the rod from falling into the tank, but as soon as pressure is subsequently developed in the tank, as a result 20 of the chemical action of the acid on the alkaline material in the basket 17, this pressure will lift the stub end of the shaft 18, whereupon the collar 34, which may be provided with a gasket, will seal the tank 25 against leakage of pressure at this point.

In practice, the system of the present invention may be either a dry or wet pipe system. That is to say, the pipe 10 and the laterals 13 may be normally filled either with 30 a liquid or by compressed air.

In the event liquid is employed, the pressure on the diaphragm 21 will be hydrostatic pressure, whereas in the event air is employed, the pressure on said diaphragm, 35 will, manifestly, be air pressure. Either air or water may be initially introduced into the system through a filling pipe 36 provided with a valve 37 by means of which the system may be sealed after it is filled sufficiently to depress the diaphragm 21 and hold the same in depressed condition for the purpose of supporting the wire basket 17 in elevated position. In practice, however, the pressure exerted on the diaphragm 21 is 40 preferably such that it will more than overbalance the weight of the wire basket and its contents so that slight leakage through the system will not effect an inadvertent starting of the system into operation. Sufficient pressure is preferably employed to permit of slow leaks, so that the system will only become inoperative in the event of fire, resulting in the opening of one or more of the sprinkler heads.

The adjustment of the ends of the weights of the basket upon the diaphragm may be readily accomplished by providing a compensating balance weight 38 which may be mounted on the detent 19 and may be slid to and fro thereon to obtain proper regulation of the pressure, which will be necessary to release the stem 18 and put the system into operation.

The system is brought into operation by 45 releasing the wire basket 17 in the manner

described, so that it will fall into the acid vessel 16. This basket may be guided through its descent by guides 39, as shown in Figure 1, so that when the basket falls into the acid, it will be in upright position. 70 The specific gravity of the contents of the basket is, in practice, considerably less than the specific gravity of the acid, so that when the basket is dropped, it will not immediately sink to the base of the acid vessel 16, 75 but at first will substantially float on the surface thereof, until the acid conducting the alkaline material into the basket, gradually saturates the same and effects a gradual depression of the basket. In this way, the 80 pressure is gradually built up and thereafter is maintained substantially uniform until the entire contents of the basket are acted upon by the acid.

The pressure generated within the casing 85 3 through the reaction of the acid on the alkaline material is transmitted through the connections 4 and 5 to the tanks 1 and 2 above the surface of the material therein; and since the formation of such pressure has 90 been the result of the opening of one or more of the sprinkler heads, an uneven condition of pressures will exist between the pressure interior of the tank and the pressures in the pipes 6 and 7 which have been 95 vented through the opening of the sprinkler head. As a result of these uneven pressure conditions, the material within the tanks 1 and 2 will be forced through their respective outlet pipes 6 and 7, will be mixed at 100 the service 18 and, in mixed condition, will pass through the pipe 9, and through the check valve 15 into the stand pipe 10, and thence into and through such laterals as contain sprinkler heads, to finally be discharged 105 through the open heads.

This discharging will continue until either all of the material in the tanks 1 and 2 is exhausted, or until the pressure is released within the tank 3. In practice, I find it 110 convenient to provide means whereby the tanks 1 and 2 may be vented at any time desired to cause the cessation of flow of material therefrom should the fire be quickly extinguished and to thereby provide against 115 unnecessary damage to property by surplus spraying of the same.

This may be accomplished in the present system by providing a pipe 40, which leads from the interior of the casing of the tank 120 3 through the various floors of the building or to various appropriate locations from which it may be desired to control the flow.

At suitable intervals, the pipe 40 has 125 therein vent valves 41, which are manually operable and if any one of these valves is open, the pressure being generated in the tank 3 will be allowed to escape through the opened vent valve 41 and will cease to exert pressure on the materials in the tanks 130

1 and 2, so that the spraying will cease, and any remaining solution in tanks 1 and 2 will be saved.

5 Retrograde flow of the materials already in the pipe 10 into the tanks 1 and 2 is precluded by the check valve 15, the sealing member 15^a of which will immediately assume a closed position.

10 While the present invention is not necessarily limited to any particular style of 70 sprinkler heads which may be employed, I prefer to use that form shown in Figure 3 of the drawings, as I have found the construction therein shown to operate with far 75 greater efficiency than any of the sprinkler heads now in use. As hereinbefore stated, the use of an ordinary sprinkler head in a foam system, is detrimental to the best results as the foam is broken up so fine and the 80 gas allowed to escape, that it ceases to operate with maximum efficiency.

15 In Figure 3, I have shown a structure, 85 through the use of which, the gas is thoroughly entrained and comes from the head 90 in the form of well defined relatively large bubbles conducive to mechanism efficient 95 in the extinguishing of the fire. In this figure, 42 designates, what is in the main, a well known type of sprinkler head. It embodies 100 a casting 43, the lower end of which is threaded and is adapted to normally screw 105 into a connection provided in one of the laterals of the sprinkler system. The casting 110 43 is moreover usually provided with a valve 115 seat, on which is adapted to seat a disc having a gasket and this disk is normally seated by a pair of cooperating arms 44, brought 120 into proper adjusted relation by an adjusting screw 45 and maintained in this position 125 to hold the valve sealed by a fusible link 46. When the link becomes fused, the arms 44 usually release the disk and allow the 130 sprinkler to operate.

135 However, in the present invention, I interpose between the sprinkler and the laterals 13, a dome-like construction and eliminate the sealing disk normally associated with the casing 42 and seat said disk which is designated in the drawings by the reference numeral 47, upon the valve seat of a fixture 49, included in the laterals. The arms 44 instead of operating directly upon the disk 47, hold the disk 47 normally seated through 140 an intermediate strut 50, which is preferably substantially triangular or of other polygonal cross section. So long as the fusible link is intact, the disk 47 will be maintained seated, but when the link disrupts the arms 44 will fall away and the pressure 145 within the laterals will force the disk 47 free from its seat. The strut 50, however, is preferably slightly tapered in an upward direction, so that when the valve is forced off its seat with a rush, the strut 50 is shot 150 upwardly and its tapered edges wedged in

the opening of the casting 43, through which it passes. In this manner, it is frequently wedged or gripped in position and will not fall again by gravity, but will leave the outlet duct 51 of the lateral 13 open 70 to permit of the exit of the mixture of foam forming material and acid.

75 The sprinkler casting 43 is mounted on an inverted cup-shaped dome 52, which is, in turn, supported by posts or spacers 53 from 80 an oppositely shaped base or cup portion 54. The base portion 54 is mounted on the connection 49 and forms with the dome 52 a chamber into which the material upon 85 leaving the duct 51 is discharged. The material discharged within the chamber substantially fills the same before it finds exit therefrom in any appreciable quantities. However, after the chamber is filled, a continued passage of the material into the 90 chamber forces the residual material therefrom in the form of relatively large bubbles 95 after the manner shown in Figure 3. The dome may be provided with outlet openings 100 55, but the major portion of the discharge is between the upper edge of the base portion and the lower edge of the dome. It is found in practice that a substantially umbrella or canopy shaped delivery results. Moreover, foam is more efficiently produced 105 by passing the foam forming solution through the chamber as it leaves the laterals and before it is discharged on the fire. The reason for this is that air in the chamber becomes entrained in the solution and causes 110 the formation of bubbles containing fire extinguishing gas.

115 The material is never broken up into a fine spray as in ordinary sprinkler heads, but the fire extinguishing gas is carried in 120 the form of relatively large bubbles in such manner that it will be brought into direct 125 proximity with the fire and blanket the same.

130 It will be noted, particularly from Figure 1, that each of the laterals 13 are bent down slightly adjacent the stand pipe, as at 13', so that the inlet to each lateral is at the highest point thereof. I find this construction desirable in a wet pipe system, 135 since it permits of the maintaining of a calcium chloride non-freezing solution in the laterals at all times and if one lateral comes into operation in the event of a local fire, all the other laterals are not automatically drained as in prior systems.

140 Having thus fully described the invention, what I claim as new and desire to secure by Letters Patent is:

145 1. A fire sprinkler system embodying a closed container for an acid, a second closed container for an alkaline foam forming solution, a pressure chamber communicating with the acid and alkaline foam forming solution chambers and adapted to 150

- contain materials for generating pressure, means for normally maintaining the materials separate from one another, a stand pipe or main, laterals associated therewith, automatic sprinkler heads associated with the laterals, branch pipes leading from the stand pipe to the individual containers, and means controlled by the sprinkler heads for permitting the pressure-forming materials to 10 come together, whereby pressure is generated and is communicated to the acid and foam forming containers, for the purpose of forcing the acid through its respective branch pipes to the main and the foam forming solution through its respective branch pipe to the main, said acid and foam forming solution being commingled with and mixed within the main pipe and discharged as 15 foam from one or more sprinkler heads.
- 20 2. In a firesprinkler system, a stand pipe or main, laterals associated therewith, automatic sprinkler heads in said laterals, a diaphragm regulator associated with the stand pipe, a pressure chamber, a body of acid in 25 the pressure chamber, a body of alkali also in the pressure chamber and normally maintained in suspended position above the acid by the diaphragm regulator associated with the stand pipe, sufficient pressure being normally present in the stand pipe to maintain 30 the diaphragm regulator in condition to support the body of alkali, until such time as one or more of the sprinkler heads is released whereupon the alkali comes in contact with the acid and pressure is formed in 35 the pressure chamber, in combination with a source of alkaline foam forming solution, and a source of acid, both of which sources being in communication with the pressure chamber and also communicate with the stand pipe for the purpose of utilizing the pressure formed in the pressure chamber to force the alkaline solution and acid from their sources into the stand pipe in which they are commingled and discharged from the sprinkler head or heads.
3. In a fire sprinkler system, a source of alkaline solution, a source of acid, a distributing pipe provided with an automatically operable valved outlet, with which distributing pipe both of the sources are in communication, a pressure chamber, also communicating with said sources of alkaline solution and acid, a body of acid in the pressure chamber, a body of alkali in the pressure chamber, and means for maintaining a predetermined pressure within the distributing pipe, and means controlled by an appreciable fall in such pressure due to the opening of the valved outlet of the distributing pipe, for effecting a reaction between the alkali and the acid in the pressure chamber, whereby the pressure resulting from such reaction is communicated to the source of acid and alkaline solution for the purpose of forcing the alkaline solution and acid into the delivery pipe where they are commingled and find exit from the valved outlet to form a foam.

In testimony whereof, I have signed my name to this specification.

OSCAR J. HOLMES.
